FIG. 1.

FIG. 2.

FIG. 3.

FIG. 4.

FIG. 5.

Inventor:
Rudolf Thormann
by Karl Kiertel
Atty.

UNITED STATES PATENT OFFICE.

RUDOLF THORMANN, OF COETHEN-ANHALT, GERMANY.

PENDULUM FOR CLOCKS.

Application filed October 28, 1925, Serial No. 65,387, and in Germany October 23, 1924.

My invention relates to pendulums for clocks and more particularly to the adjusting or setting mechanism by which the position of weight or "bob" at the lower end 5 of the pendulum rod can be correctly set with regards to the correct time keeping of the clock.

It is one of the objects of my invention to thus design said mechanism that the 10 weight will automatically and positively follow every movement—even the slightest upwards or downwards—of the adjusting member.

Another object of my invention is to 15 eliminate the effects of wear at the faces where the adjusting member and the weight are in contact. It is a fact known among expert watch makers that even said faces will wear off in course of time, which noticeably interferes with the correct time keeping.

Another object of my invention is to positively prevent any upsetting of the correctly 20 set pendulum weight due to vibrations and shocks to which the clocks are frequently subjected through passing trains, trolley cars, heavy machinery, etc. at work nearby, and last but not least due to shocks occurring in the course of transportation from manufacturer to seller and buyer.

It has been proved by experience in many cases that vibrations and shocks will cause the mostly unlocked set-screws or 25 threaded nuts at the lower end of clock pendulums to turn little by little, thereby gravely interfering with the correct time keeping of the clock.

With these and other objects in view I 30 have designed an improved mechanism for adjusting and setting the weight of clock pendulums, the essential features of which have been briefly set forth in the appended claims.

The nature of this invention and the scope 35 of my claims will be more fully understood from the following specifications taken together with the accompanying drawing in which—

Fig. 1 is a view of a clock pendulum from 40 the rear,

Fig. 2 is a side view and a plan of the pendulum and the clamping device respectively,

Fig. 3 shows the pendulum with a modification of the clamping device,

Figs. 4 and 5 are rear and side elevations of the pendulum weight with clamping devices of different design.

a designates the pendulum rod to the lower end of which the weight or "bob" *b* 60 is attached. In the embodiment of my invention, illustrated in the drawing, the said weights *b* are shown as being made in the form of hollow lens-shaped discs, but the specific form and design of the weight 65 per se is by no means an essential feature of my invention and not intimately correlated therewith.

The weight *b* is preferably in slight frictional contact with the rod *a*, e. g. by means 70 of a resilient tongue formed by two slots *i*, *i* at the rear face of the weight.

At its lower end the rod *a* is provided with a threaded wire *c*, carrying a nut *d* and serving as weight setting mechanism. 75

According to my invention the nut *d* is clamped to the weight preferably by resilient clamping means so as to positively control the upward and downward shifting of the weight *b*. 80

In the modification shown in Figs. 1 and 2 by way of an example, the clamping means comprises a V-shaped metal wire, the legs *f* of which at *g* engage by means of hooks. 85 slots *i*, *i* in the rear face *b* and have waved resilient sections *f'*.

At its lower end of the clamping member an eye *h* is formed, so as to engage the nut *d* from underneath.

The nut *d* positions the weight *b* by means 90 of an intermediary member *e*, adapted to contact with the periphery of weight *b*.

In the modification, shown in Fig. 3, the clamping member consists of a wire *l* having a waved section *l'* and engaging the weight 95 *b* by means of a hook at *o*.

In the modified form, shown in Fig. 4, the clamping wire *m* has a resilient section, represented by a helical spring *n*, and it engages the front face of the weight by means of a 100 hook *p*.

In the modification shown in Fig. 5 the clamping member *q* engages the nut *d* by means of an interposed spring *s*. 105

In all the modifications shown the clamping wire at its lower end is formed with an eye portion *h* surrounding the threaded bolt *c* and engaging the nut *d* from underneath.

What I claim is:

1. In a pendulum for clocks, a rod having 110

- a lower threaded end, a hollow weight having a pair of downwardly extending slots forming a spring tongue adapted to frictionally engage the rod, a nut having a seat for the weight threaded upon the rod, and a tensioning member having one portion thereof engaging the upper portion of the weight and its opposite end engaging the lower face of said nut.
- 10 2. In a pendulum for clocks, a rod having a lower threaded end, a hollow weight having a pair of downwardly diverging slots forming a spring tongue adapted to frictionally engage the rod, a nut having a seat for the weight threaded upon the rod, and a tensioning member having a pair of upwardly diverging arms engaging the lower
- 15

ends of the slots and having a loop intermediate its ends engaging the lower face of the nut.

20 3. In a pendulum for clocks, a rod having a lower threaded end, a hollow weight mounted upon said rod having a pair of downwardly diverging slots therein forming a spring tongue adapted to frictionally engage an intermediate portion of the rod, a nut having a seat for the weight threaded upon the rod, and a V-shaped tensioning member having its upper ends engaging the ends of the slots and an intermediate portion engaging the under face of the nut.

25 30 In testimony whereof I have signed my name to this specification.

RUDOLF THORMANN.
